UNITED STATES PATENT OFFICE.

CHARLES B. OVERTON, OF VIGOR, VIRGINIA.

CHAIR.

Application filed June 8, 1926. Serial No. 114,496.

This invention relates to self-propelled rolling chairs, and aims to provide a rolling chair of a novel construction wherein the same may be folded into a small and compact article to facilitate the storing and transporting thereof.

An important object of the invention is to provide a folding rolling chair of a construction wherein the seat, which is removable, will, when in its active position, act as a means for holding the rolling chair in its extended position.

A still further object of the invention is to provide a rolling chair which may be readily and easily folded to its inoperative and operative positions.

With the foregoing and other objects in view which will appear as the description proceeds, the invention resides in the combination and arrangement of parts and in the details of construction hereinafter described and claimed; it being understood that changes in the precise embodiment of the invention herein disclosed, may be made within the scope of what is claimed, without departing from the spirit of the invention.

Referring to the drawings:

Figure 1 is a front elevational view of a rolling chair constructed in accordance with the invention and showing the same in its operative position.

Figure 2 is a front elevational view of the chair showing the same in a partially folded condition.

Figure 3 is a side elevational view of the chair in its operative position.

Figure 4 is a perspective view illustrating one portion of the chair and showing the axle construction in detail.

Figure 5 is a perspective view illustrating the brake.

Referring to the drawings in detail, the chair includes a pair of side sections 5 and 6 respectively, the side sections being identical in construction and include spaced parallel bars 7 and 8 respectively, the bars 7 being formed with cut out portions arranged adjacent to the rear ends thereof, which cut out portions accommodate the axles 9 which are of the stub type, and provided with upwardly extended portions 10 that are formed with openings to accommodate the bolts 11 that pass through the upper bars 8.

At the rear of the bars 7 and 8 are vertical bars 12 to which the bars 7 and 8 are secured, as by means of the straps 13, so

that the bars 7 and 8 are held in spaced relation with each other.

The forward ends of the bars 7 and 8 of each frame are connected by means of the bars 14 that have their lower ends extended below the bars 7, where they are provided with suitable sockets for the reception of the vertical shafts 15 that are provided with forks 16 and in which the front or small wheels 17 are mounted.

Secured to the under surfaces of the bars 7 are rearwardly extended inclined bars 18 that have their rear ends spaced from the surface over which the rolling chair is moving, so that should the chair tilt rearwardly these bars 18 will act to stop such rearward tilting. In order to cushion the movement of the bars 18, springs 19 are provided and disposed between the bars 7 and 18 as clearly shown by Figure 4 of the drawings.

At the rear end of each bar 8 is a metallic strap 20 that has an upwardly extending end portion 21 adapted to engage one edge of the vertical arm 22, there being provided bolt openings in the members 21 and 22 for the reception of bolts to secure the arm 22 in position with respect to its supporting member.

At the upper ends of the arms 22 are bifurcated members 23 adapted to grasp the ends of the upper bar 24 of the seat back 25 so that the upper portion of the seat back will be securely held against movement.

Bars 26 form the side bars of the seat back 25 and have their lower ends reduced as at 27 and providing pins adapted to be positioned within the keepers 28 that are secured to the rear edge of the seat portion 29.

This seat portion 28 is formed with notches 30 at its corners, which notches fit behind the front and rear bars 12 and 14, of the side frames of the rolling chair. Thus it will be seen that due to this construction, the seat and seat back act to hold the side frames in proper spaced relation with each other when the chair is in its operative position.

Brace bars 31 are employed at the front and rear of the chair and have their outer ends pivotally connected to the side frames of the chair, as clearly shown by Figures 1 and 2 of the drawings, the brace bars being arranged in pairs and pivotally connected at 32. These brace bars act to prevent spreading of the frame section when the chair is in its operative condition, while

the seat and back sections act to prevent the sections from moving towards each other.

The arms of the chair are indicated at 33 and have their rear ends connected with the arms 22, the forward ends being connected with the upper ends of the bars 34 that are secured to each frame of the chair.

The wheels that support the chair are indicated by the reference character 35 and are mounted on the axles 9 as shown by the drawings. Operating frames indicated at 36 include pairs of bars formed with outwardly curved portions defining forks 37, the lower ends of the forks being formed with openings to permit the forks to be slid onto the axles 9 to connect the operating frames to the axles.

One of the bars of each frame 36 extends inwardly and upwardly providing a clearance for the arms 38 that support the bearings 39 at their upper ends, in which bearings shafts 40 operate. These shafts 40 have controlling handles 41 on their inner ends and sprockets 42 on their outer ends, the sprockets 42 being designed to transmit motion to the substantially large sprockets 43 that are secured to the wheels 35 to rotate the wheels 35 and propel the rolling chair.

In order that an adjustment of the handles 41 may be made, the upper ends of the bars forming the frames 36 are formed with elongated openings 44 to accommodate the bolt 45 that also passes through the arms 38. Thus it will be seen that by lengthening the chain connecting sprockets 42 and 43, the bearing member 39 may be moved upwardly. The foot rest of the chair is indicated by the reference character 46 and is supported by means of the downwardly extended bars 47 that are pivotally connected to the frames at 48, and also have pivotal connection with the foot rest 46 at 49 so that the bars 47 may be moved towards each other when the rolling chair is to be moved to its folded position. The foot rest is also braced against rearward movement by means of the bar 50 that is shown in Figure 3 as extending rearwardly where it connects with the axle, the forward end being connected with the foot rest 46.

A brake rod indicated at 51 is shown as supported adjacent to one of the arms 33 and has swivel connection with arm 52 which is pivotally supported by means of the pivot pin 52', and on which the shoe 53 is mounted to engage the wheel 35 associated therewith when the handle 54 at the upper end of the rod 51 is forced downwardly, thereby braking the wheel 35.

A lever 56 is shown as formed with a curved end 57 defining a shoe mounted adjacent to and designed to engage the wheel at the opposite side of the chair. This lever

56 connects with the brake rod 51 through 55 the link 58 and laterally extended arm 59, there being provided a coiled spring 60 connected with the arm 59 to return the arm 59 to its initial position after it has been actuated. Thus when it is desired to operate the brake 57, the rod is rotated by means of the handle 54.

When it is desired to brake both wheels simultaneously, the rod 51 is forced downwardly and rotated at the same time.

From the foregoing it will be seen that to fold the chair, it is only necessary to remove the seat and seat back from their positions between the side frames of the chair, and remove the lower bracing bars 31 at 75 their points of connection with the side frame, whereupon the side frames may be moved towards each other and the device folded into a small and compact article.

I claim:

1. A folding rolling chair including side frame sections, means for pivotally connecting the sections, a seat and seat back removably connected, said seat and seat back being supported by the frames and adapted 90 to hold the frames in spaced relation with each other, and wheels for supporting the frames.

2. A folding rolling chair including frames, each of said frames embodying 95 parallel upper and lower bars, means for holding the bars in spaced relation with each other, means for pivotally connecting the frames, and a removable seat and seat back arranged between the frames and supported thereby.

3. A folding rolling chair including frames, said frames being wheel-supported, pivoted bars for connecting the front and rear ends of the frames, a seat section adapted to be positioned on the frames, said seat sections having keepers on its rear edge, a seat back having reduced portions adapted to extend into the keepers, to hold the seat back to the seat, and means for securing the seat back against movement at its upper end.

4. A folding rolling chair including frames, means for pivotally connecting the frames to permit the frames to be moved towards and away from each other, each of said frames including a rear upwardly extended arm, said arm having bifurcated end portions, a seat positioned on the frames, a seat back removably connected with the seat and having the upper portion thereof arranged between the furcations of the bifurcated portions of the arms, and wheels for supporting the frames.

In testimony that I claim the foregoing as my own, I have hereto affixed my signature.

CHARLES B. OVERTON.
